(57) **CLAIM**

The ornamental design for an overbed light, as shown and described.

DESCRIPTION

FIG. 1 is a top perspective view of an overbed light showing my new design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The broken lines contained herein illustrate portions of the overbed light that form no part of the claimed design.
